UNITED STATES PATENT OFFICE.

HENRY E. WOODBURY, OF WASHINGTON, DISTRICT OF COLUMBIA.

DOCUMENT FILE OR HOLDER.

Specification of Letters Patent No. 11,504, dated August 8, 1854.

To all whom it may concern:

Be it known that I, HENRY E. WOODBURY, of the city of Washington, in the District of Columbia, have invented a Useful and Improved Document File or Holder, of which the following is a full, clear, and exact description, reference being had to the accompanying drawing, which forms part of this specification, and in which—

10 Figure 1, represents a top view or plan of my improved document file open, with folded documents contained therein. Fig. 2, represents a vertical longitudinal section thereof with the documents partly raised 15 for the purpose of reading the indorsements on their backs.

In filing public and private documents it is usual to fold them into regular forms and sizes and indorse each one separately with 20 an epitome of its contents—date of reception or note having reference to the particular character of business to which it relates,—tie, band, or put in wrapper the several documents relating to the same business 25 accumulating from time to time. Where the business is of a varied character of course many such files have to be kept, and in many instances, as for example in the various departments of the Government, where 30 frequent reference to papers on file is requisite, much trouble and inconvenience arises, both in filing away new papers and in abstracting old ones for examination in tying and untying the tape or band which is necessary to hold tightly, the several documents composing the file, together to prevent them scattering; and such frequent tying and untying not only exposes papers to loss but by the abrasion of the 35 tape or band on the edges of the folded documents rubs and wears them into holes, whereas their perfect preservation, in some instances for an indefinite period, is a matter of the utmost importance.

40 To obviate such injury inconvenience and annoyance in the filing of folded documents is the object of my improvement which consists of a box or compartment (A) the depth, and width across of which corresponds to the length and width of the folded document or paper, and is of any convenient length according to the number of papers designed to be held in one file. The sides of this box may either be made of

flexible or elastic material to enable them 55 to yield to papers of different widths being filed therein and to protect the edges of the papers from injurious abrasion; or the sides of the box may be of hard and inflexible material. Within this box is a loose 60 holder or platen (B) that is of nearly the same width and depth as the box inside, which is hung or attached at its center to a coiled spring (C) the other end of which is fastened against the back end of the box 65 serves to force up the loose holder or platen (B) toward the front end of the box. A lid (D) covers the opening in the top of the box.

The lid of the box being opened, the folded papers or documents are inserted between the front end of the box and the platen (B) by pushing back the platen which by its elastic pressure holds the papers thus 70 inserted firmly in their place, and so from time to time fresh documents may be added 75 till the box is full, or old papers be abstracted without much or any delay and without displacing or removing from their hold the other papers in the file, and by the 80 manner in which the loose holder or platen is hung and acted upon, the greatest facility is afforded for examining the indorsements of the several papers, in search after one or more particular documents on file, 85 as the flexibility of the platen or its capability of being bent or leaned back (as represented in Fig. 2) admits of all or several of the papers being drawn partly out of the box (A) and of being pushed back or 90 separated at their top ends to read their indorsements without releasing the papers from the hold of the spring platen.

Of course any number of these box or compartment files may be built together to 95 form a cabinet, or may be arranged upon shelves, or each be a portable and separate file as represented in the drawing, and in addition to the advantages already specified, they are simple and durable, preserve 100 the contents perfectly free from dust, also from destruction by mice, which are very apt when papers are stored upon shelves or in pigeon holes to cut them in pieces and make their nest among the fragments; and 105 the additional expense of fitting up a room or office with them instead of with pigeon holes would be but trifling compared with

the neatness of the apartment, the cleanliness and preservation of the documents, and the facility of reference thereto.

What I claim as my invention and desire 5 to secure by Letters Patent is—

The box or compartment document file constructed and operating substantially as herein described, and consisting of a box part (A) and spring platen or holder (B) 10 the said holder being hung or attached to the spring at its back in such a manner as to give a flexible character to the holder and admit of its being leaned back or to either side to facilitate the reading of the indorse-

ments and the abstraction from or insertion of certain papers to the file without releasing the other papers from the hold of the platen, and the whole forming a more convenient file for the filing away of folded documents and to protect them from 20 abrasion &c as herein set forth.

In testimony whereof, I have hereunto subscribed my name this 14th day of July 1854.

HENRY E. WOODBURY.
